UNITED STATES PATENT OFFICE.

JOHN E. LONG, OF MULTNOMAH, OREGON.

ELECTRIC SIGN.

Application filed January 30, 1926. Serial No. 84,926.

My invention relates to electric display signs as a class.

The object of my invention is to provide certain improvements of and in the device shown in my prior invention covered by Letters Patent No. 1,572,212, issued February 9, 1926.

The improvements now contemplated are to provide a series of circuit breakers along one side of the perforated paper tape, which will function to break the circuit, and extinguish the lamps in case the tape breaks, also to provide one or more series of circuit controls along the opposite border of the tape which will function to cause a flash or spot light to be directed toward objects which may be referred to in the sign display, or to control any other apparatus which it may be desired to operate in connection with the main light display. These objects, as well as other advantages, I attain by the construction, combination and arrangement of parts illustrated in the accompanying drawings which form a part hereof.

Fig. I is a front elevation of the device with parts in section and somewhat diagrammatic.

Fig. II is a plan view of the bottom of the receptacle showing wire terminals.

Fig. III is a transverse view of the device in Fig. I with parts in section.

Fig. IV is a plan view of part of a paper tape, showing perforations therein arranged in characters to control lamp circuits to display lamps and other controls in related arrangement.

Like characters refer to like parts in the views.

There is a frame 1 of insulating material. Within the frame a common terminal plate 2 is secured, the same being provided with sockets to receive electrical lamps of common type with one terminal thereof in contact with the plate. Lamps 3 are shown in the plate. A circuit wire 4 extends from the plate 2 and is connected oppositely as will be later described. The lamps are positioned in the plate to allow a light display of them in character and design arrangement. Below the lamp frame is a quadrilateral trough formed receptacle 5 of insulating material, supported on standards 6 in horizontal position. The bottom of the receptacle has orifices 7 arranged in positions correspondingly related to the lamps in place on the plate 2. Wires 8 extend from the respective

lamp terminals, opposed to those having the plate contact, to and through the related orifices 7 until the free ends are flush with the upper surface of the receptacle bottom and are there rigidly secured to form electrical contacts. A perforated tape 9 of non-conducting material extends in sliding engagement along the bottom of the receptacle, passing about rollers 10—11, within and without the receptacle, arranged to allow the tape to move in an endless strip flush with the bottom of the receptacle. Mechanism 12 is provided to rotate the roller 11 and draw the tape as stated and illustrated. The tape has perforations arranged in characters or designs, as for example those shown in Fig. IV at 14, and in relation to the wire terminals in the bottom of the receptacle and hence also in relation to the lamps in place on the display board. A grid 15 is positioned in the receptacle to engage the tape and cause it to slide snugly along the bottom and prevent it from buckling. Within the receptacle a bath of mercury 16 is placed, which rests upon the tape, retained there by the receptacle walls. A circuit wire 17 has its free end immersed in the mercury and extends therefrom to a connection with one terminal of a battery 18. From the opposing terminal of the battery a circuit wire 19 extends to and through a circuit breaker 20, having a solenoid 21 of common type. From the circuit breaker a wire 22 extends to a connection with the plate wire 4. Within the receptacle, at one side of the series of orifices 7 and in parallel alignment with same is a series of like orifices 23 in the bottom, spaced a convenient distance apart. Conducting wires 24 have one terminal in these orifices, flush with the receptacle bottom, their opposing ends are connected with a common wire 25. From the wire 25 a connected circuit wire 26 extends to and about the solenoid 21 and to a connection with the wire 4 at 27. The portion of the tape which passes over the terminals in the orifices 23 is unperforated. In the bottom of the receptacle on the opposite side of the lamp terminal orifices and in parallel alignment with their series are a third and fourth series of like orifices 28—29, spaced a pre-determined distance apart. Conducting wires 30—31, respectively, having one terminal in these orifices flush with the bottom of the receptacle, extend from there to a connection with any other auxiliary apparatus terminal which it is desired

2

to operate together with the lamp display, for example a switch to cause a flash light of different colors, a spot light, an apparatus to rotate or move an object under these mentioned lights, etc. From a connection with the wire 22 at the position 27 a return circuit wire 32 extends to a convenient opposing connection terminal of the auxiliary apparatus, whatever it may be. The tape 9 has perforations 33—34 respectively in alignment with the terminals in the orifices 28—29 or slots as at 35 may be provided. These perforations or slots are spaced a pre-determined distance apart. There may be one or 10 more of the series of wire terminals as in the orifices 28—29 and a corresponding number of tape perforations as at 33—34. If the tape breaks or buckles so as to allow mercury to pass below it and engage the terminals of the wires 24, the solenoid 21 is actuated, causing the circuit beyond the point 27 to be broken. Briefly, the improvement 20 upon my prior apparatus resides in this circuit breaking control of the lamps and in 25 the added circuits to control the operation of auxiliary apparatus.

It will now be seen that when the mechanism to rotate the roller 11 is started, the roller draws the endless tape through the mercury bath, the terminals in the bottom registering with the tape perforations at pre-determined times. The design or character perforations admit the mercury connecting element to contact with the terminals at 7 below the tape which will close 30 the circuit and cause related lamps 3 to be illuminated in sequence as the tape progresses until the whole of the characters or designs thus arranged upon a given portion 35 of the tape are produced by related, illuminated lamps on the field above. As the tape thus progresses, should it break, that portion moving forward has but a short distance to travel, when the nearest terminal 40 of the tape are produced by related, illuminated lamps on the field above. As the tape thus progresses, should it break, that portion moving forward has but a short distance to travel, when the nearest terminal 45 23 will be uncovered and the mercury enter into contact with it closing a circuit through the wires 24—25—26—22, which actuates the solenoid 21 and operates the circuit breaker 20 to break the circuit of the wire 4 at 27 50 and thus extinguish the lamps and prevent them from being lighted by circuits through the terminals 7 and at the same time break the circuit for the auxiliary apparatus. The terminal series 28 and 29 are connected by 55 wires 30 and 31 with one terminal respectively of any one or more apparatus which it is desired to have operated in connection with the lamp display field, such as a spot light, for example. The wire 32 extends 60 from the wire 22 at the point 27 to the opposite terminal of such apparatus. It will now be seen that the tape perforations 33 and 34 are arranged in sequence to admit the mercury at pre-determined times to a connection which will operate the auxiliary apparatus referred to. These perforations may also be slots, to extend the time in which such apparatus is operated, as for example the slot 35. It is obvious that as any of the tape perforations or slots pass 70 beyond the terminals, the circuits are broken and the apparatus ceases to operate. The object of the independent apparatus, for an example, is to display some notice on the lamp field, such as, "Special to-day", and following this, one apparatus having a spot light might be operated to illuminate an object on a revolving pedestal to which the notice is desired to call attention in a show window. A second apparatus to rotate the 80 pedestal slowly could be operated by use of the other independent circuit. The lamp illumination and auxiliary apparatus can be synchronized accurately with my device 85 to produce results described and a great variety of other combinations for display advertising purposes. The improvements described are new and useful and are easily and economically adaptable to my prior device. Likewise the automatic circuit breaker 90 is new and useful as it will prevent the entire lamp field illumination and auxiliary apparatus operating at a loss when the tape breaks or buckles and fails to work in the 95 manner intended.

I claim—

1. In an electric sign device provided with a receptacle of insulating material with a horizontal bottom and a centrally disposed plurality of terminals flush with the upper bottom surface, a battery in connection therewith, a liquid terminal upon the receptacle bottom, also a tape of non-conducting material having a plurality of apertures registerable with said central terminals, adapted to close and break main circuits between the terminals, the battery and the liquid terminal; the combination of the following elements; a like single, circuit breaking terminal in the receptacle bottom in a line parallel with the central terminals, a tape of the kind first described having its unperforated margin slidable over said single terminal, a circuit breaker positioned on the main circuit of the device adjacent to a battery, a wire extending from said single terminal to a connection on the main circuit with the breaker, and a wire extending from the liquid terminal to the opposing terminal of a battery, said elements being adapted to break the main circuit through the breaker and automatically close a short circuit through said single terminal when the tape breaks or buckles and allows the liquid terminal to make contact with the single terminal. 110

2. In an electric sign device provided with a receptacle of insulating material with a horizontal bottom and a centrally disposed plurality of terminals flush with the upper 115

bottom surface, a battery in connection therewith, a liquid terminal upon the receptacle bottom, also a tape of non-conducting material having a plurality of apertures registrable with said central terminals, adapted to close and break main circuits between the terminals, the battery and the liquid terminal; the combination of the following elements; a series of like circuit breaking terminals in the receptacle bottom along a line parallel with the central ones, a tape of the kind first described having its unperforated margin slidable over said parallel terminals, a circuit breaker positioned on

the main circuit of the device adjacent to 15 a battery, wires extending from said parallel terminals to a connection on the main circuit with the breaker, and wires extending from the liquid terminal to the opposing terminal of a battery, said elements being adapted to break the main circuit through the breaker and automatically close a short circuit through said parallel terminals when the tape breaks or buckles and allows the liquid terminal to contact with the 25 parallel terminals.

JOHN E. LONG.
